ATTORNEY

UNITED STATES PATENT OFFICE.

ERNEST S. GOLDY, OF PHILADELPHIA, PENNSYLVANIA.

TOOTH-BRUSH.

1,007,864.

Specification of Letters Patent. Patented Nov. 7, 1911.

Application filed May 28, 1910. Serial No. 563,924.

To all whom it may concern:

Be it known that I, ERNEST S. GOLDY, a citizen of the United States, and a resident of Philadelphia, in the county of Philadelphia and State of Pennsylvania, have invented certain new and useful Improvements in Tooth-Brushes, of which the following is a specification, reference being had to the accompanying drawings.

10 This invention particularly relates to tooth-brushes of the class wherein the brush-head is adapted to be inclosed in a protective casing, when not in use.

The principal objects of this invention are 15 to provide a tooth-brush with a removable hollow handle, which is preferably shaped from a primarily flat unitary stamping of sheet material, so formed as to provide a closure for the brush-head when not in use; 20 to provide a socket into which the brush shank is fitted when operatively connected with said handle; and to provide a bayonet connection between said shank and handle to insure their rigid connection when in 25 operative relation.

The brush constructed in accordance with this invention is advantageous, in that it prevents distortion of the bristles when not in use, and prevents their unsanitary contact with unclean objects, as, for instance, the pocket of the user, thus preventing moistening the pocket lining; and, furthermore, when the brush-head is inclosed in the handle, the structure is reduced to substantially 35 one-half its normal length as when said brush-head and handle are operatively related.

The form of this invention, hereinafter described, provides a brush with a detachable handle, which forms a closure for the brush-head when not in use, and which has an extended portion, preferably cylindrical, forming a socket, and having a substantially spirally disposed slot, said socket being arranged to receive the conical shank of the brush-head, which may be snugly fitted in said socket, and which is provided with a lug engageable with said slot to prevent accidental displacement of said brush-head when 50 its shank is operatively engaged with the socket in said extended portion.

This invention further includes the various novel features of construction and arrangement hereinafter more definitely set forth.

In the accompanying drawings, Figure 1

is a perspective view of the brush and its detachable handle in operative relation; Fig. 2 is a side elevation of the brush handle, showing the brush detached therefrom and inclosed therein, in inoperative relation; Fig. 3 is a transverse vertical sectional view taken on the line 3—3 in Fig. 2; Fig. 4 is a vertical longitudinal sectional view taken centrally through the brush handle, showing the brush in elevation, operatively connected with said handle; and Fig. 5 is a plan view of the sheet metal stamping extended in a plane and ready for folding to form the brush handle.

In said figures, the casing 1 includes the bottom wall 2, the side walls 3 and 4, the top wall 5, and end wall 6. Said side wall is provided with lugs 8 and 9, which are extended through the apertures 10 and 11 in the top wall 5, and headed over to form the substantially rectangular casing, best shown in Fig. 1. The wall 6 is provided with a lug 14, which is extended through the aperture 15 in said wall 5 and headed over, and forms the end inclosure for said casing. The casing thus formed conveniently provides a handle for the brush, and the bottom wall 2 of said casing is provided with the extension 16, which is preferably cylindiform, to provide a socket for the conical shank 17 of the brush-head 18, which is provided with the projecting pin or lug 21, which, when said shank is operatively connected with the handle, is slidably engaged with the bayonet slot 22 in the extension 16 forming the walls of said socket.

As best shown in Fig. 5, the casing 1 is formed from a unitary stamping of sheet material 25, preferably metal, which is folded upon the dot and dash lines therein indicated, to form the handle of the brush, and which at the same time provides a casing for the reception and protection of said brush when detached, as shown in Fig. 2, said brush being engaged in operative position, as shown in Figs. 1 and 4, by telescopically fitting the shank 17 into the socket formed by the walls of the extension 16 with its lug 21 engaged with the bayonet slot 22, so that, as may be readily seen, as said shank is fitted into said socket the brush is given substantially a quarter turn, and the lug 21 prevents accidental longitudinal displacement of said brush with respect to its handle.

It is obvious that a tooth-brush con-

structed in accordance with this invention is advantageous, in that the brush portion, being separable from the handle, may be readily replaced by a new brush when worn.

b It is not desired to limit this invention to the precise details of construction and arrangement herein set forth, as it is obvious that various modifications may be made therein without departing from the essential 10 features of the invention as defined in the appended claims.

Having thus described my invention, I claim:

1. A tooth-brush comprising a detachable 15 handle, forming a casing for said brush when detached, the lower wall of said casing being extended and formed into a socket arranged to receive the shank of said brush, and having means arranged to engage means 20 on said shank to prevent the longitudinal movement of said brush with respect to said handle when operatively connected therewith.

2. A tooth-brush comprising a detachable

handle, forming a casing for said brush 25 when detached, one wall of said casing being extended to form a cylindrical socket arranged to receive the shank of said brush, and a slot circumferentially disposed with respect to said socket, arranged to receive 30 means on said shank, the walls of said slot preventing the accidental longitudinal displacement of said brush when operatively connected with said handle.

3. A tooth-brush comprising a detachable 35 handle, forming a casing for said brush when detached, one wall of said casing being extended outwardly and turned to form a split cylindrical socket arranged to receive the shank of said brush, and to form an 40 extension of said shank.

In witness whereof, I have hereunto set my hand this 26th day of May, A. D., 1910.

ERNEST S. GOLDY.
